UNITED STATES PATENT OFFICE.

IGNACE L. BOSCH, OF RICHWOOD, WEST VIRGINIA.

ARTIFICIAL HAND.

1,050,607.

Specification of Letters Patent. Patented Jan. 14, 1913.

Application filed February 21, 1912. Serial No. 679,010.

To all whom it may concern:

Be it known that I, IGNACE L. BOSCH, a citizen of the United States, residing at Richwood, in the county of Nicholas and 5 State of West Virginia, have invented new and useful Improvements in Artificial Hands, of which the following is a specification.

This invention relates to artificial hands 10 and the object of the invention is to provide a simple and efficient device of this character which may be operated to accomplish the many necessary duties required with a facility almost equaling the ability of the 15 natural hand.

Further objects of this invention will appear as the following specific description is read in connection with the accompanying drawing, which forms a part of this application, and in which:—

Figure 1 is a side elevation. Fig. 2 is a similar view showing the jaws in open position. Fig. 3 is a perspective view of the device removed from the arm.

Referring more particularly to the drawing, the device is shown connected to an ordinary artificial forearm which consists of a head 1 apertured to receive the projection 2. This projection constitutes an extension 30 of a rod or bar 3 which is provided intermediate its ends with a pivoting ear 4 and beyond the ear is bent into a loop or curve 5 and terminates in a gripping jaw 6. This member comprises one part of a substantially plier-like construction, the opposite member being indicated at 7 and being pivoted to the ear 4. The outer end or the portion beyond the pivot point is constructed in the same manner to the member 3, that 40 is, it is provided with a looped curved portion 8 and a gripping jaw 9 adapted to coact with the jaw 6. The portion in the rear of the pivot point extends at an angle to the rod 3 and is provided with an upturned end 45 10 to which is connected an operating chain or cable 11 having a ring 12 carried at its inner end. Surrounding the ear 4 is a spring whose free end 13 is provided with a lateral hook to engage the under side of the 50 member 7 in the rear of the pivot point, being thus adapted to normally hold the jaws

in closed position. Removably connected to the ring 12 by means of a snap fastener 14 is a strap 15 preferably provided in its opposite end with a loop, not shown, to engage 55 the opposite shoulder of the wearer.

In practice, the strap 15 passes up the arm and across the shoulders where it is connected with the opposite shoulder in such a manner that a jerk or bodily movement of 60 the opposite shoulder will pull upon the member 7 against the tension of the spring 13 and open the jaws. By releasing the tension upon the strap, the spring will close 65 the jaws and is of sufficient strength to hold 70 an object of ten or more pounds. Upon the opposite side of the device from the spring, a hook 16 is secured to the pivotal ear upon the rod 3, which hook is adapted to receive a pencil or to utilize the hand for carrying 75 a bucket or other similar device. The loops or curved portions 5 and 8 are constructed for the purpose of surrounding the neck of a bottle so that the same may be readily lifted or handled while the cap or closure 80 member is being removed.

What is claimed is:—

An artificial hand comprising a mounting member, an extension carried thereby and having a loop therein adjacent its outer end, 80 a clamping member pivoted to the mounting member and having a loop to correspond with the loop in said extension, jaws carried by the clamping member and extension and projecting beyond the loops parallel 85 with the extension, an angular arm on the clamping member having a laterally offset end, a spring surrounding the pivotal point of said extension and clamping member and connected adjacent the outer end of said arm 90 for normally holding the jaws in engagement with each other, a flexible member connected to the offset end of said arm, an operating strap, and a removable connection between the operating strap and the flexible 95 member.

In testimony whereof I affix my signature in presence of two witnesses.

IGNACE L. BOSCH.
